BUMPER CARRIER

Sterling W. Pelton, Western Springs, Paul M. Pelton, West Chicago, and Jerry E. Morgan, Clarendon Hills, Ill., assignors to Advanced Fibre-Glass, Ltd.

Filed Feb. 19, 1974, Ser. No. 443,714

Term of patent 14 years

Int. Cl. D12—I6

U.S. Cl. D12—157

Fig 1

Fig 2

Fig 3

*Fig 4**Fig 5**Fig 6**Fig 7*FIG. 1 is a perspective view of a bumper carrier showing our new design, it being understood that the broken lines are for illustrative purposes only;

FIG. 2 is a top plan view thereof;

FIG. 3 is a bottom plan thereof;

FIG. 4 is a front elevational view thereof;

FIG. 5 is a side elevational view thereof;

FIG. 6 is a rear elevational view thereof; and

FIG. 7 is a side elevational view thereof opposite to that shown in FIG. 5.

We claim:

The ornamental design of a bumper carrier, substantially as shown and described.
